UNITED STATES PATENT OFFICE.

CLARENCE JOHNSON, OF KENDALLVILLE, INDIANA.

NECKTIE.

Application filed March 1, 1926. Serial No. 91,546.

This invention relates to improvements in neck ties of the type which are tied in an orderly fashion at the factory, and it is the object of the present invention to provide 5 an exceptionally simple and inexpensive yet a desirable and efficient attaching means associated with a tie of this type.

With the foregoing in view, the invention resides in the novel subject matter herein- 10 after described and claimed, the description being supplemented by the accompanying drawings.

Figure 1 is a perspective view showing the tie applied;

15 Figure 2 is a horizontal sectional view as indicated by line 2-2 of Fig. 1;

Figure 3 is a perspective view of the tie as manufactured and placed on sale, looking toward the rear.

20 In the drawings above briefly described, the numeral 4, designated a bow tie of conventional form, whose central portion is formed by a band 5. Running between the rear reach of this band and the body portion 25 of the tie 4 is a single rather short strip of elastic 6, the central portion of this elastic strip being stitched at 7 to the band 5. At its ends, the strip 6 is provided with attaching hooks 8 having sharp points or spurs

which are preferably formed by bending 30 portions of sheet metal plates 9, to which the ends of the elastic strip are anchored.

The strip 6, plates 9 and hooks 8 are interposed between the inner and outer folds of a collar, and said hooks are engaged with 35 the inner fold by forcing the sharp points or spurs into the fold as shown clearly in Figure 2, the strip 6 being of course placed under tension to hold the hooks and collar properly engaged. 40

By the novel construction disclosed, not only can the device be produced much more cheaply than ties having an elastic band to extend entirely around the neck, but the article will be more convenient and more 45 comfortable to the wearer.

I claim:

An article of manufacture comprising a neck tie, a short strip of elastic secured midway between its ends to the rear side of said 50 tie, and hooks on the ends of said elastic strip said hooks having sharp pointed ends adapted to be forced into the inner fold of a collar when the strip is placed under tension. 55

In testimony whereof I have hereunto affixed my signature.

CLARENCE JOHNSON.
